UNITED STATES PATENT OFFICE.

MINNIE A. HOUSHOLDER, OF CHICAGO, ILLINOIS.

PORTABLE ADJUSTABLE ADJUSTING-TABLE FOR CHIROPRACTIC USE.

1,276,655.

Specification of Letters Patent. Patented Aug. 20, 1918.

Application filed November 27, 1915. Serial No. 63,761.

To all whom it may concern:

Be it known that I, MINNIE A. Housholder, a citizen of the United States, residing at Chicago, in the county of Cook and

5 State of Illinois, have invented a certain new and useful Improvement in Portable Adjustable Adjusting-Tables for Chiropractic Use, of which the following is a specification.

10 In work of this character, it is absolutely essential that the operator secures perfect relaxation on the part of the patient. Tables for this purpose, which have been made in the past, with which I am familiar, are subject to the objection that they, by reason of 15 their formation, are unable to accommodate the various figures of different patients, so that the patients complain of undue pressure, and therefore are unable to relax. Another 20 objectionable feature is that they will not accommodate heavy persons due to the fact that they are not rigid in their construction, thus rendering it difficult to secure proper adjustment.

25 My invention has for its object to provide a table which shall be portable, but which shall be so constructed as to be absolutely rigid when in use, and to construct it in such a way that the patient may be fully relaxed 30 when on the table, in this manner preventing any bruising of the muscles caused by trying to make adjustments when the muscles are contracted, and to accomplish this result without producing a table which will 35 be too heavy to be carried about by the operator from his office to the patient's home, when required.

40 My means of accomplishing the foregoing objects may be more readily understood by having reference to the accompanying drawings, which are hereunto annexed and are a part of this specification, in which:

Figure 1 is a perspective view of my improved table, opened.

45 Fig. 2 is a top or plan view of the same.

Fig. 3 is a perspective view of my table closed and ready to be carried about.

Fig. 4 is a perspective view of the elevating leg.

50 Similar reference numerals refer to similar parts throughout the entire description.

As shown in the drawings, the table consists of two sections or tables 1 and 2, which are provided with legs 3 and 4, 5 and 6, respectively, thus forming two small tables.

These legs are hinged to the sections 1 and 2, adjacent the corners, which permits them to fold inwardly when the table is not in use.

The section 2 is provided with a slot 7 in 60 the center thereof, and as shown in Fig. 1, a cushion 8 is also provided which is slotted to correspond with the slot 7. This construction provides for the accommodation of the nose of the patient when lying face 65 down, and enables the cervicals and upper dorsals to be kept in perfect alinement, thus greatly facilitating the adjustment, a result which is impossible where the patient has to lie on a table which is not provided with 70 this slot, and therefore has to twist the head, and thus the cervicals and upper dorsals are pushed out of alinement, making proper and correct adjustment difficult, if not impossible.

75 It is well known that if there is the slightest fear in the patient's mind, that he will not be able to relax perfectly, and where the ordinary table is used, which simply leaves an opening between the two tables, the patient fears that he will be pushed between the two sections, with the result that the operator is unable to secure proper adjustment. I overcome this by providing two coil springs 10, which extend from the section or table 1, to the section or table 2, upon which is rested a cushion 9. These springs are detachable, so as to permit the table to be folded up, and also to permit either one of the tables to be turned around for different 80 positions required in making various 85 adjustments.

90 The legs are stiffened by struts 11 and 12, which serve to brace the legs rigidly and firmly in position. They are detachably secured to the legs so as to permit their removal when it is desired to fold the table up.

95 A brace 13 provided with a plurality of slots 14, is provided to secure the tables 1 and 2, any desired distance apart, to accommodate a person of any height or weight. This distance apart is necessary in order to prevent injury to the bones and soft parts when adjusting, which would be the case if made on a solid table.

100 I provide legs 15, shown in Fig. 4, which may be secured to the legs 6 of the table 2, by means of the bolts 20 and wing nuts 21 to permit its elevation for accommodating different positions which may be required 110

to effect proper adjustment, slots 22 being provided to permit the placing of these elevating legs in different positions.

The closing of the table is accomplished as follows:

The rods 11 and 12 are removed from the legs 3 and 4, and 5 and 6. These legs are then folded inside of the tables or sections 1 and 2. The brace 13 is placed inside of one of the two sections. The braces 11 and 12 are also placed intermediate the legs. The cushions and coil springs are placed on the top of the legs. The two sections 1 and 2 are then placed in juxtaposition and secured together by fasteners 17, which may be of any suitable or convenient style for effecting this purpose. It may be found desirable to provide dowel pins to assist in holding the two sections in position. A handle 18, is provided for the convenience of the operator.

The slot 7, is filled with a board 19, which is fitted to and coincides with the opening and is provided with suitable fasteners to hold it in place when the table is closed. One end of the section or table 2, is formed with an inclined plane 20, which is absolutely essential where the patient lies upon the face, or back, as it prevents contraction of the muscles due to the pressure of a full-busted person when lying on the face, and when lying on the back accommodates the buttocks.

It will be apparent from the foregoing, that the construction is such that it is possible by the use of such a table to secure complete relaxation of the patient, thus greatly facilitating the correct adjustment.

Copies of this patent may be obtained for five cents each, by addressing the "Commissioner of Patents, Washington, D. C.

Having described my invention what I regard as new, and desire to secure by Letters Patent is:

1. A portable adjusting table comprising two sections, each of said sections having four legs, said legs being hinged to their respective sections, whereby they may be folded inwardly, two coil springs extending between the two sections and detachably secured thereto, a detachable brace placed between the two sections, there being a plurality of notches in said brace whereby the sections can be braced the desired distance apart, a handle secured to the outside of the table, and means to hold the two sections securely together when folded up in the form of a suitcase, there being a slot in one of said sections and an inclined plane on the upper surface of one section adjacent one end.

2. A portable adjusting table comprising two sections each of said sections having four legs, each of said legs being hinged to their respective sections whereby the legs may be folded inwardly, said table legs being braced by struts detachably secured thereto, there being coil springs which extend from one table section to the other, a detachable brace placed between the two sections, there being a plurality of notches in said brace, whereby the sections can be braced the desired distance apart, there being a slot in one of said sections and an inclined plane on the upper surface of one section adjacent one end.

In testimony whereof, I have signed the foregoing specification.

MINNIE A. HOUSHOLDER.
